UNITED STATES PATENT OFFICE

119,808

DESIGN FOR A WHEAT CAKE GRILL

Emma Merritt, Bay City, Mich.

Application June 20, 1939, Serial No. 85,584

Term of patent 3½ years

To all whom it may concern:

Be it known that I, Emma Merritt, a citizen of the United States, and a resident of Bay City, in the county of Bay and State of Michigan, have invented a new, original, and ornamental Design for Wheat Cake Grills, of which the following is a specification, reference being had to the accompanying drawing, forming part thereof.

Fig. 1 is a front perspective view of the wheat cake grill, showing my design; and

Fig. 2 is a perspective view of one of the removable tray elements of the wheat cake grill.

The rear and opposite end of the wheat cake grill are identical with the front and end shown in Figure 1 of the drawing, except that the electrical plug connection is omitted from the end not shown.

I claim:

The ornamental design for a wheat cake grill, as shown and described.

EMMA MERRITT.
